Patented Oct. 14, 1919.

FIG. 1.

FIG. 2

FIG. 3.

H. G. Hutchinson
Inventor

By Geo. P. Kimmel
Attorney

UNITED STATES PATENT OFFICE.

HENRY G. HUTCHINSON, OF CLEVELAND, OHIO.

HEATER FOR AUTOMOBILE-BODIES.

1,318,875.

Specification of Letters Patent. Patented Oct. 14, 1919.

Application filed March 17, 1917. Serial No. 155,528.

To all whom it may concern:

Be it known that I, HENRY G. HUTCHINSON, a citizen of the United States, and resident of Cleveland, in the county of Cuyahoga and State of Ohio, have invented certain new and useful Improvements in Heaters for Automobile-Bodies, of which the following is a specification.

The present invention relates to improvements in heaters and has more especial reference to a novel automobile body and heater, wherein, the exhaust or spent gases from the engine are utilized as the heating medium.

It is a more specific object of the invention to provide novelly arranged baffles within the heater, the same being so arranged as to cause the heating of the entire device to an even and uniform temperature and preventing the waste of heat.

The improvements in the details and arrangements of parts will be apparent from an inspection of the accompanying drawings, in connection with the specific description hereinafter contained, and wherein the preferred embodiment of the invention is disclosed for the purpose of imparting a full understanding of the same.

In the drawings:

Figure 1 is a bottom plan view of my improved heater;

Fig. 2 is a horizontal section therethrough; and

Fig. 3 is a vertical transverse section through the same.

Referring now more specifically to the drawings, in connection with which like reference numerals will refer to the same parts throughout the several views, there is provided a housing 1, substantially rectangular in shape and having formed in one corner thereof an intake opening 2 communicating with the exhaust manifold of the automobile engine, while in the diagonally opposite corner there is provided an exhaust opening which receives therein a discharge nozzle 3, the outer extremity of which is flattened as shown in Fig. 3. Laterally extending apertured lugs 4 are

formed upon the extremities of the housing and obviously, serve as means for facilitating the securing of the same to the desired portion of the vehicle body. It is of course to be understood, that the housing is provided with a top or closure plate and further, that

the said plate is detachably engaged therewith whereby access may be had to the interior of the housing should it be desired.

Within the housing, there is arranged a plurality of oppositely disposed longitudinally extending webs or baffle plates generally indicated by the numeral 5, the free extremities of each of the said plates being arranged in spaced relation from the particular walls of the housing as adjacent the same, in order that continuous circulation of the heated exhaust gases may be had therethrough. Upon the outermost baffle plates, there are arranged laterally offset plates 6 which plates may be and preferably are formed integral therewith at a point in proximity of the intake and exhaust openings of the housing. By so arranging the laterally offset plates 6, it will be understood that the heated exhaust gases will be caused to thoroughly engage all parts of the housing before discharge through the discharge nozzle 3 of the same. As a consequence, the housing will be heated to an even and uniform temperature. By reducing the discharge extremity of the nozzle 3, the discharge of spent gases from the housing 1 is delayed, thereby, permitting the same to fully heat the housing before a discharge therefrom.

The top of the housing 1 is recessed as at 7 and has arranged therein a plurality of longitudinally extending ribs 8, the ribs having the ends thereof open, whereby to permit a continuous circulation of air between the same and as a consequence, offering a greater heated area. It of course is to be understood that the top of the housing which carries the longitudinal ribs may be formed integral therewith or, if desired, may be detachably secured thereto whereby the same may be removed as it becomes necessary.

I claim:

1. A heater of the character described comprising a housing having an inlet in one corner and an outlet in a second corner, baffle plates extending longitudinally in the housing alternately from opposite end walls thereof and having their free end portions extending in overlapping relation, the outer baffle plates terminating short of the inlet and outlet, and intermediate baffle plates extending through the housing and having extensions extending to the outer baffle

plates intermediate the ends of the adjacent baffle plates and the inlet and outlet.

2. A heater of the character described comprising a housing having an inlet and an outlet, a cover for the housing having upstanding side flanges, and heat radiating ribs upon the upper face of the cover ex-

tending longitudinally between the flanges and terminating in a plane flush with the upper edges of the flanges.

In testimony whereof, I affix my signature hereto.

HENRY G. HUTCHINSON,
